[57] CLAIM

The ornamental design for an automobile wheel cover, as shown.

DESCRIPTION

FIG. 1 is a front elevational view of an automobile wheel cover showing my new design;

FIG. 2 is a rear elevational view thereof;

FIG. 3 is a side elevational view thereof from the right of FIG. 1; and

FIG. 4 is a cross sectional view thereof taken on the line IV—IV of FIG. 1.
